(57) **CLAIM**

I claim the ornamental design for a lid for beverage container, as shown and described.

DESCRIPTION

FIG. 1 is a perspective view of a lid for beverage container showing my new design, with a cap shown in dashed lines; FIG. 2 is a top plan view thereof (with the cap not shown); FIG. 3 is a bottom plan view thereof (with the cap not shown);

FIG. 4 is a right side elevational view thereof (with the cap not shown);

FIG. 5 is a left side elevational view thereof (with the cap not shown);

FIG. 6 is a front elevational view thereof (with the cap not shown); and,

FIG. 7 is a rear elevational view thereof (with the cap not shown).

Dashed lines representing a threaded portion for coupling to a container (in FIGS. 1, 4, 5, 6, and 7), the cap (in FIG. 1), a drinking opening (in FIGS. 1 and 2), a vent opening (in FIGS. 1-3), and a ramp configuration (in FIG. 3) are for purposes of illustrating portions of a lid and form no part of the claimed design.
